BONE CONDUCTION HEARING AID

Emmanuel Christ Nicholides, New York, N. Y.,
assignor, by mesne assignments, to Sonotone
Corporation, New York, N. Y., a corporation of
New York

Application August 11, 1933, Serial No. 684,712

7 Claims. (Cl. 179—107)

This invention relates to bone-conduction hearing-aids and it has among its objects an improved inertia-reaction bone-conduction receiver of small size suitable for inconspicuous wear by the user and able to impart hearing-inducing mechanical vibrations to the sound-conducting bone structure of a hard of hearing person for inducing sound in his hearing center.

The features and objects of the invention will be best understood from the following description of exemplifications thereof, reference being had to the accompanying drawings, wherein—

Fig. 1 is a view of the head of a person carrying a bone-conduction receiver exemplifying the invention, the associated elements of the hearing-aid being shown diagrammatically;

Fig. 2 is a vertical sectional view of the receiver along line 2—2 of Fig. 3;

Fig. 3 is a horizontal sectional view of the receiver along line 3—3 of Fig. 2;

Fig. 4 is a vertical sectional view of the receiver along line 4—4 of Fig. 3;

Fig. 5 is a horizontal sectional view through the receiver along line 5—5 of Fig. 2;

Fig. 6 is an elevational view of the base wall of the receiver casing, the inner part of it being shown in section;

Fig. 7 is a top view of the receiver as worn on the head;

Figs. 8, 9, 10 and 11 are views similar to Figs. 2, 3, 4 and 5, respectively, of a modified form of the receiver;

Figs. 12 and 13 are side elevational and top views partially in section of modifications of the receiver shown in Figs. 2 to 5, and 8 to 11, respectively; and

Figs. 14 and 15 show an elevational rear view and a side elevational, partially-sectional view of modifications of receivers of the type shown in Figs. 2 to 5, and 8 to 11, respectively.

According to the invention, the casing of an inertia-reaction bone-conduction receiver utilizing a floating vibrator unit for imparting hearing-inducing inertia-reaction forces to a casing wall is provided with a curved external coupling surface for securing a good impedance match between the enclosed vibratory structure and the bone structure of the user against which the coupling surface is pressed. Large inertia-reaction forces are developed within the receiver casing by utilizing an electromagnetic vibrating structure having set screws enabling accurate fixing of the critical magnetic gap distance of the enclosed vibrating unit essential for producing with the small receiver the great amount of

hearing-inducing vibratory energy required for imparting hearing by bone conduction.

A bone-conduction receiver of my invention as actually built and used is shown in Figs. 1 to 7. It is made in the form of a small completely-closed casing 1 and is shown in Fig. 1 held against the mastoid bone by means of a head band clamped over the head. Sound-frequency oscillatory currents may be supplied to the receiver from any suitable source, such as a portable set, comprising a transmitter microphone 2 connected through a cutout switch in series with a battery 3 and a microphone amplifier 4 and cord 5 to terminal plugs 6 leading into the casing 1. The transmitter microphone, the microphone amplifier and all the other elements of the circuit are small and may be easily hidden in the clothing of the user. Sound waves acting upon the diaphragm of the transmitter 2 induce corresponding currents in the amplifier 4 and the amplified speech currents are impressed through cord 5 on the mechanism within the receiver casing 1.

The construction of the receiver is shown in detail in Figs. 2 to 7. It comprises a small casing having a base 7 and an elongated cover 8 fitting against the edges of the base and attached thereto by means of screws 9, and terminal block 11 rising above the base.

To permit easy coupling of the receiver surface against the bone structure 12, the casing 1 is adjustably mounted on a bracket 13 embracing the upper sides of the casing cover and having inward pivot projections 14 fitting into suitable cooperating depressions 15 in the cover walls to support the casing and press its exposed base surface into close engagement with the bone structure 12. This pressure is supplied by the head band 16 which is clamped over the head, its lower end being secured to the upper cross piece of the bracket 13 and exerting the pressure supplied by the head band through the bracket arms 13 and the pivots 14 on the casing base, and therethrough on the bone structure.

Inside the casing 1 is mounted an electromagnetic vibrator unit 24 comprising a magnetic core structure 25 and a diaphragm 26. The magnetic core structure comprises an elongated permanent-magnet plate 27 carrying two L-shaped soft iron pole pieces 28 having inwardly projecting arms 29 ending in pole faces 30 forming small gaps 31 with the adjacent surface of the diaphragm strip 26. The outwardly extending pole piece arms are firmly attached over soft iron spacers 32 to the adjacent ends of core plate 27.

by rivet extensions 33 of non-magnetic clamping blocks 34. Only the outer ends of the pole piece arms are thus connected to the permanent magnet core, the inner portions of these arms being spaced from the core by the gaps extending from the inner edges of the spacers 32.

To permit accurate fixing of the small critical pole gaps 31 of the order of about $\frac{1}{3}$ to $\frac{1}{2}$ of a thousandth of an inch between the pole faces 30 and the diaphragm strip 26, set screws 37 are screwed in through the magnet core plate 27 into threaded holes in the overlying arm portion of the two pole pieces 28. By turning the set screws 37, the pole faces 30 may be moved to increase or decrease the gap 30 in front of the pole faces. In assembling the magnetic core structure 25, its upwardly projecting pole pieces 28 are made to terminate at the same level as the flat surfaces of the supporting blocks 32 that are to hold the ends of the diaphragm. After completely assembling the core structure, the upper surface of the pole pieces and the blocks 32 are ground to the same level. The coils 41 are then mounted in place and the flat diaphragm is secured by its screws 35 to the ends of the blocks 34. Thereupon the adjusting screws 37 are turned until the pole pieces are brought to a position wherein they do not freeze and are fit for operation.

Although the gap is made about $\frac{1}{3}$ to $\frac{2}{3}$ of a mil long, satisfactory results may also be obtained with somewhat larger gaps.

Two inducing coils 41 mounted on the pole pieces 29 are connected to contact lugs 46 riveted at their lower ends to terminal bushings 47 fastened in the terminal block 20 at the bottom end of the base for engaging the plugs 6 of the supply cords 5.

The diaphragm 26 has an enlarged center portion lying above the pole faces 30 and its ends are rigidly clamped by screws 35 to the flat upper surfaces of the non-magnetic spacer blocks 34. The center portion 51 of the diaphragm bridges the space between the pole faces 30 of the core and provides a path for the flux between the two core pole faces 30 through the gaps 31, connected in series. The end portions of the diaphragm are narrower than the center portion 51 and merge into center portion 51 by gradually widening intermediate portions.

The rigidity, thickness and shape of the diaphragm 26 are chosen to give it a stiffness necessary to prevent freezing between the diaphragm and the core pole faces. Its stiffness is chosen to prevent freezing of the diaphragm at a gap of about $\frac{1}{3}$ to $\frac{1}{2}$ mil and its resonance is at about 1,000 cycles per second. In the vibrator shown in Figs. 2 to 7, the diaphragm is made of cold rolled steel and has a thickness of 15 mils. The operating gap between the diaphragm and the core is about $\frac{1}{2}$ mil. By making its end portions narrow and the center portion 51 gradually wider, the end portions have the smallest stiffness, the stiffness gradually increasing in the regions near the center portion where it reaches its greatest value. This limits the maximum deflections of the center portion of the diaphragm and enables using of a thinner diaphragm. The gradual increase of the stiffness also prevents formation of vibration nodes on the diaphragm.

As shown in Figs. 4 to 6, the vibrator composed of the relatively heavy core structure 25 and the relatively light diaphragm 26 is mounted and supported as a unit on the inner center portion of the casing base 7, by attaching the center portion of the diaphragm to an anchor member 55

rigidly imbedded in the body of the base 7. The anchor member 55 is of metal, like brass, and has a large plate-shaped rear portion 56 imbedded conical depressions 57, 58 imbedded within the rigid mold body of synthetic resin material. The anchor member 55 is provided with an inwardly protruding, short anchor block 59 to which the lateral ends of center portion 51 of the diaphragm are rigidly secured by screws 60 threaded into holes 61.

When completely assembled the casing base 7 carries on its anchor member 55 the center piece 51 of the diaphragm 26. The two projecting narrow extensions of the diaphragm 26 carry, in turn, on the blocks 34 the completely assembled rigid core structure including the core members 27, 28 and coils 41, so that the entire vibrator structure is carried by the anchor 55 at the center of the casing base 7 of the casing. The spacing between the vibrator structure and the adjacent walls is sufficient to permit free vibration thereof on the anchor 55 towards and away from the base. Since the vibration amplitude is small, very little clearance is needed. By making the vibrator structure elongated and symmetrical with respect to the point of its anchoring point on the base, the vibratory forces are symmetrically imparted to the base and uniformly distributed thereover, securing a good coupling between the base 7 and the bone structure underlying it. A satisfactory impedance match between the vibration of the vibrator unit in the casing and the mass of base 7 and the bone structure is thus obtained.

In the bone-conduction vibrator as actually constructed and in use, the dimensions and weights of the principal elements are as follows: The permanent magnet bar is of tungsten steel, has a length of 1.125, a width of .475, and a thickness of .093 inches; the pole pieces are of soft iron steel, have a thickness of .050, and a total length of .600 inch. The diaphragm is of cold rolled steel, half hard temper, and has a length of 1.125, a maximum width of the center of .590, and of the end portions of .275 inch, and a thickness of .015 inch; the center portion has a length of .175 inch at the outer edge, and a length of .375 inch at the junction with the narrow middle extensions. The total effective vibratory mass of the diaphragm unit, including the diaphragm and the base attached thereto, is 7.8 grams; and the stiffness of the diaphragm is about 8×10^6 dynes per centimeter. The gaps have an equal length of about $\frac{1}{2}$ mil when the armature diaphragm is under the action of the permanent magnetic field. The assembled vibrator mechanism with the casing has a length of $1\frac{1}{8}$, a width of $1\frac{1}{4}$, and a height of $\frac{1}{2}$ inches. The total weight of the complete vibrator with the casing is about 20 grams.

The bone-conduction receiver described above will, notwithstanding its small size and small weight, transmit into the bone structure of the head of a person of impaired hearing more vibratory power than required for giving satisfactory hearing. Transmission of the large amounts of power is obtained by the provision of a minute critical gap spacing between the diaphragm and the core pole faces of the order of $\frac{1}{2}$ mil, and by the use of a diaphragm proportioned to permit vibrations with an amplitude of about $\frac{1}{2}$ mil while preventing gap freezing. Balanced transfer of the vibrations and prevention of distortions on the diaphragm is secured by the symmetric support of the vibratory mass at the junction of 75

the central portion of the diaphragm to the central portion of the base.

Only the central nodal portion of the vibrator mechanism is utilized for coupling the vibrator mechanism to the bone structure, and substantially the entire mass of the vibrator mechanism is carried in a floating condition and utilized to produce the inertia-reaction forces required for transmitting hearing-inducing vibratory energy to the bone structure of the user.

In Figs. 8 to 11 I have shown a modified form of the bone-conduction receiver of my invention. It comprises a casing 103 having a base 104 and an elongated cover 105 fitting the base having a contact surface 106 held against the bone structure 107.

To an anchor member 110 rigidly imbedded within the base is secured the center portion 111 of a diaphragm 112 having extensions 113 clamped to the core.

The core structure 114 comprises an elongated rigid permanent magnet bar 115 magnetized to have one pole, for instance, a north pole 116 in the center, and two south poles 117 at its ends.

A soft iron center core 120 is secured by a threaded end portion 121 in a threaded hole 122 within the center of the permanent magnet bar 115 making the opposite end of the projecting core portion 120 the negative pole of the magnet core. The flat south-pole ends 117 of the permanent magnet bar 115 are secured to soft iron core blocks 125 by riveting extensions 126 of these blocks into holes within the bar ends.

The permanent magnet bar 115 with the two soft iron blocks 125 and the center core member 120 constitute an E-shaped magnetic core structure having a center core with a pole face 128 of one polarity, and two end cores 125 with pole faces of opposite polarity.

The threaded mounting of the supported end of the center core within the hole of the magnetic bar 115 enables accurate adjustment and maintenance of an accurate minute gap of the order of about $\frac{1}{2}$ mil between the center portion of the diaphragm lying over the center core pole face. The core portion lying above the threaded end is wider than the threaded portion and a lock washer 130 is placed between it and the inner wall of the bar 115 to lock the core 120 in position.

An inducing coil 132 is connected through flexible wires 134 to connecting lugs 135 attached to bushings 136 mounted within the terminal block 138.

The unit of Figs. 8 to 11 is thus freely suspended within the casing and is free to vibrate within the casing on its anchor coupling with the base. As in the vibrator of Figs. 2 to 4, it will develop a great vibratory power while imparting to the bone structure large vibratory forces of small displacement and maintaining its operating gap in non-freezing position.

Because of the balanced transmission of power from the symmetrical vibrator structure through its symmetrical coupling connection over the base to the bone structure and the uniform distribution of the forces over a large area of the base, a close coupling is obtained between the vibrator unit within the casing and the bone structure, enabling uniform and large transfer of the power into the bone structure.

By matching the amplitudes of the vibrations impressed by the vibrator with the characteristics of the bone structure, the energy transfer to the bone structure is greatly increased. Such improved operation is obtained by increasing the

coupling area between the contact member of the receiver and the bone structure engaged thereby.

An embodiment of a bone-conduction receiver arranged to operate with an increased contact surface with large forces and small vibration amplitudes is shown in Figs. 12 and 13. The vibrator casing 150 and vibrator mechanism in its interior may be made as in the structures shown in Figs. 8 to 11, and 2 to 5. To secure better coupling of the vibration transmitting member with the bone structure, I shape the contact surface of the base 151 of the vibrator unit to conform to the shape of the bone structure. Such large contact surface can be easily provided on the outer contact surface of the base by shaping in accordance with a cast of the bone portion which it is to match. From collections of casts of the bone structures of groups of similar persons, average contact surfaces can be shaped that may be used to advantage by different persons having similar bone structures.

A bone-conduction receiver 160 having a large area vibration transfer contact surface and avoiding the necessity of making bases with different contact surfaces is shown in Figs. 14 and 15. It has a contact face 161 shaped to fit in general outline the shape of the bone structure on a predetermined portion of the skull, and has on the contact face several contact areas 162 slightly projecting above the contact face so as to grip the bone structure from several angles, with the individual contact areas shaped to engage a large area of the bone portion structure against which it rests. These projecting contact areas may have either slightly convex or slightly concave flexure so as to give in their average actions an effect of a large surface.

The bone-conduction receivers described above are inconspicuous in size, light in weight, and able to deliver more than sufficient vibratory power to induce by bone conduction satisfactory sound in the inner ear of the user. Their electromagnetic vibrator mechanism is an independent self-sustaining unit. It combines a large-mass magnetic core with a small-mass magnetic diaphragm into a symmetric low-reluctance magnetic-path structure with the core and diaphragm vibrating relatively to each other across one or more very small gaps of opposite polarity having a length of the order of about $\frac{1}{3}$ to $\frac{1}{2}$ mil at a diaphragm stiffness of a magnitude which will positively prevent gap freezing at resonance, without exceeding the freezing stiffness by more than twice. A nodal portion of the diaphragm is used as the sole support of the vibrator mechanism and has the vibrations of the unit impressed thereon. A nodal diaphragm portion is rigidly coupled to and supported on a contact member having a large concave surface engaging and pressing against a sound conducting bone structure to secure a good match of the impedance of the vibrator unit with the mass of the bone structure and a large transfer of vibratory power.

The principles underlying the invention and the various features thereof may be utilized in conjunction with hearing-aid devices in many other ways that will suggest themselves to those skilled in the art, and it is accordingly desired that the appended claims be given a broad construction commensurate with the invention.

I claim:

1. In a portable bone-conduction hearing-aid device, a bone conduction receiver, suitable for inconspicuous wear by a deafened, having two relatively movable vibratory sections, means for

- exposing said sections to the action of electric sound-frequency oscillations producing a vibratory motion between said sections, and coupling means for coupling one vibratory section to sound-inducing bone structure outside the ear canal of the user, said coupled vibratory section constituting a casing carrying said other vibratory structure in a floating condition within said casing, said floating vibrator section having sufficient 5 inertia for exerting hearing-inducing reaction forces on a wall of said casing, said wall having a concave external coupling surface shaped to impart under the action of said reaction forces convergent hearing inducing forces to spaced portions 10 of said bone structure.
2. In a portable bone-conduction hearing-aid device, a bone conduction receiver, suitable for inconspicuous wear by a deafened, having two relatively movable vibratory sections, means for 15 exposing said sections to the action of electric sound-frequency oscillations producing a vibratory motion between said sections, and coupling means for coupling one vibratory section to sound-inducing bone structure outside the ear canal of the user, said coupled vibratory section constituting a casing carrying said other vibratory structure in a floating condition within said casing, said floating vibrator section having sufficient 20 inertia for exerting hearing-inducing reaction forces on a wall of said casing, said wall having a coupling surface larger than the overlying cross sectional area of said casing shaped to impart under the action of said reaction forces hearing 25 inducing forces to spaced portions of said bone structure.
3. In a portable hearing-inducing device, a bone conduction receiver, suitable for inconspicuous wear by a deafened, having two relatively movable magnetic core members constituting a low reluctance flux path spaced by a small gap of the order of one mill, windings interlinked with said path for producing by sound-frequency current oscillations a vibratory motion between said core members, and coupling means for coupling one 30 core member to sound-inducing bone structure outside the ear canal of the user, said coupled core member constituting a part of a casing carrying the other core member in a floating vibratory condition inside said casing, said floating core member having sufficient inertia for exerting hearing-inducing reaction forces on a wall of said casing, said wall having an external concave coupling surface shaped to impart under the action of said reaction forces convergent hearing inducing forces 35 to spaced portions of said bone structure.
4. In a wearable hearing aid device, an electromagnetic bone conduction receiver of inconspicuous size comprising a driven member, a driving member of substantial mass resiliently joined to 40 said driven member to constitute therewith a vibratory structure of fixed dimensions forming a low reluctance magnetic flux path including a gap of the order of a fraction of a thousandth of an inch separating opposing pole faces of said members, said driven member constituting a part of a casing enclosing and resiliently carrying said driving member in a floating condition inside said casing, means for coupling by external pressure an exterior wall of said casing to hearing inducing 45 bone structure of the user, windings interlinked with said flux path producing under energization by audio-frequency current oscillations corresponding magnetic forces across said gap for imparting through the inertia reaction of said floating driving member hearing inducing vibratory 50
- 75

energy to said bone structure and set screw means extending through two spaced facing portions of the enclosed vibratory structure for fixing the structural relation of the floating part of the vibratory structure relatively to the driven member 5 and maintaining the dimensions of the gap at a fixed value at which the amplitude of the vibrations of said members is of the order of the gap distance while preventing freezing of the pole faces across said gap.

5. In a wearable hearing aid device, an electromagnetic bone conduction receiver of inconspicuous size comprising a driven member, a driving member including a rigid permanent magnet bar of substantial mass resiliently joined to said 10 driven member to constitute therewith a vibratory structure of fixed dimensions forming a low reluctance magnetic flux path including a gap of the order of a fraction of a thousandth of an inch separating opposing pole faces of said members, said driven member constituting a part of a casing enclosing and resiliently carrying said driving member in a floating condition inside said casing, means for coupling by external pressure an exterior wall of said casing to hearing inducing 15 bone structure of the user, windings interlinked with said flux path producing under energization by audio-frequency current oscillations corresponding magnetic forces across said gap for imparting through the inertia reaction of said floating driving member hearing inducing vibratory 20 energy to said bone structure, and set screw means extending through said rigid magnet bar and engaging another spaced facing portion of the enclosed vibratory structure for fixing the structural relation of the floating part of the vibratory structure relatively to the driven member and maintaining the dimensions of the gap at a fixed value at which the amplitude of the vibrations of said members is of the order of the gap 25 distance while preventing freezing of the pole faces across said gap.

6. In a wearable hearing aid device, an electromagnetic vibrating device of inconspicuous size suitable for wear by the user comprising a driven 30 member, a driving member of substantial mass resiliently joined to said driven member to constitute therewith a vibratory structure of fixed dimensions forming a low reluctance magnetic flux path including a gap of critical length separating opposing pole faces of said members, a casing enclosing said members, one of said members being secured to an interior wall of said casing and resiliently carrying the other member in a floating condition inside said casing, windings 35 interlinked with said flux path producing under energization by audio-frequency current oscillations corresponding magnetic forces across said gap for imparting a vibratory motion to the floating member inside said casing, and set screw means extending through one of said members and engaging another facing portion of the enclosed vibratory structure for fixing the structural relation of the floating member relatively to the member extending from said casing and maintaining the gap distance between the opposite pole faces within fixed limits while preventing freezing of the pole faces during the vibrations of said floating member.

7. In a wearable hearing aid device, an electromagnetic bone conduction receiver of inconspicuous size comprising a driven member, a driving member of substantial mass resiliently joined to said driven member to constitute therewith a vibratory structure of fixed dimensions forming a 40

70

75

low reluctance magnetic flux path including a gap of the order of a fraction of a thousandth of an inch separating opposing pole faces of said members, said driven member constituting a part of 5
5 a casing enclosing and resiliently carrying said driving member in a floating condition inside said casing, means for coupling by external pressure an exterior wall of said casing to hearing inducing bone structure of the user, windings interlinked 10
10 with said flux path producing under energization by audio-frequency current oscillations corresponding magnetic forces across said gap for imparting through the inertia reaction of said float-

ing driving member hearing inducing vibratory energy to said bone structure, and set screw means extending through a portion of said floating vibratory structure and engaging another facing portion of the enclosed vibratory structure for 5
fixing the structural relation of the floating part of the vibratory structure relatively to the driven member and maintaining the dimensions of the gap at a fixed value at which the amplitude of the vibrations of said member is of the order of 10
10 the gap distance while preventing freezing of the pole faces across said gap.

EMMANUEL C. NICHOLIDES.
